(57) **CLAIM**

The ornamental design for a pipe for vacuum cleaner, as shown and described.

DESCRIPTION

FIG. 1 is a front perspective view of a pipe for vacuum cleaner, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 of FIG. 4;

FIG. 10 is an enlarged view of the encircled portion 10 of FIG. 6;

FIG. 11 is an enlarged view of the encircled portion 11 of FIG. 7;

FIG. 12 is an enlarged view of the encircled portion 12 of FIG. 8;

FIG. 13 is a front perspective view of the pipe for vacuum cleaner shown in a state of use with the vacuum cleaner; and, FIG. 14 is a rear perspective view of the pipe for vacuum cleaner shown in a state of use with the vacuum cleaner. The broken lines depict portions of the pipe for vacuum cleaner and environmental structure that form no part of the claimed design.

The dot-dot-dash broken lines encircling enlargement portions of the design form no part of the claimed design.

1 Claim, 14 Drawing Sheets
